UNITED STATES PATENT OFFICE.

JOHN J. THACHER, OF WETHERSFIELD, CONNECTICUT, ASSIGNOR TO PRATT & WHITNEY COMPANY, OF NEW YORK, N. Y., A CORPORATION OF NEW JERSEY.

CENTERING MACHINE.

Application filed May 5, 1921. Serial No. 487,056.

To all whom it may concern:

Be it known that I, JOHN J. THACHER, a citizen of the United States, residing at Wethersfield, in the county of Hartford and State of Connecticut, have invented certain new and useful Improvements in Centering Machines, of which the following is a specification.

This invention relates to improvements in machine tool construction and particularly to an automatic center drilling machine.

It is an object of the invention to provide preferably in combination with a magazine, an improved blank transferring, centering and holding means adapted to transfer a blank from the magazine to the working position, to center the same in position for operation thereon by the tools, and to hold the blank in position while the tools perform thereon.

Another object of the invention is to provide improved means to feed the tool spindles toward and from the work, such operation being preferably automatically performed in timed relation with the blank transferring, centering and holding mechanism.

Another object of the invention is to provide an improved spindle driving and locking means adapted to be shifted to drive the spindle at the desired speed or to lock the same against rotation.

A further object of the invention resides in the novel mounting of the power means on the machine, such mounting being so constructed as to readily receive thereon either an electric motor or a belt pulley driving mechanism adapted to receive power from any suitable source.

Another object of the invention resides in a blank guiding and supporting means, such means being adapted in one position to guide the blanks into a receiving receptacle as they are released from the holding means and in another position to receive and support such blanks.

With the above and other objects in view, my invention consists in the features of construction and operation set forth in the following specification and illustrated in the accompanying drawings. In such drawings annexed hereto and forming a part of this specification, I have shown my invention as embodied in a center drilling machine but it will be understood that the

invention can be otherwise embodied and that the drawings are not to be construed as defining or limiting the scope of the invention, the claims appended to this specification being relied upon for that purpose. 60

In the drawings:

Figure 1 is a front elevation of a center drilling machine having the improved mechanism embodied therein.

Fig. 2 is a plan view thereof. 65

Fig. 3 is a rear elevation of the machine.

Fig. 4 is an elevation of one end thereof.

Fig. 5 is an enlarged detail view showing particularly the blank transferring, centering and holding means. 70

Fig. 6 is an enlarged view showing particularly the means for adjusting the stroke of the spindles.

Fig. 6^a is a detail view illustrating more in detail certain of the mechanism shown in Fig. 6. 75

Fig. 7 is an enlarged detail plan view of one of the carrier jaws.

Fig. 8 is an end view thereof.

Fig. 9 is a side elevation thereof. 80

Fig. 10 is an enlarged detail view, partially in section showing the spindle driving and locking means.

Fig. 11 is a plan view thereof.

Fig. 12 is a detail view taken on the line 12—12 of Fig. 10. 85

Fig. 13 is a detail view showing a belt pulley attachment mounted in position to drive one of the spindles, such attachment being illustrated as substituted for the electric motor drive shown in Fig. 10. 90

Fig. 14 is an end view thereof.

Fig. 15 is a view similar to Fig. 13 and showing a belt pulley attachment applied to the other spindle. 95

Fig. 16 is an end view thereof.

Fig. 17 is a detail view showing a belt pulley attachment mounted in position to operate the several parts of the machine, such construction being illustrated as substituted for the lower electric motor shown in Fig. 3. 100

Fig. 18 is an enlarged fragmentary perspective view of one end of the machine.

Fig. 19 is a fragmentary plan view taken on line 19—19 of Fig. 6. 105

Fig. 20 is a fragmentary sectional view taken on line 20—20 of Fig. 3.

Work pieces or blanks which are to be placed in a lathe for operation thereon must 110

first have their ends accurately drilled or countersunk at the center thereof to receive the lathe centers. This operation is ordinarily performed in a hand or semi-automatic machine. The primary object of the present invention is to provide an automatic machine for performing this function. In its broad aspect such machine comprises the following principal parts: a 5 magazine for holding a quantity of blanks, transferring, centering and holding mechanism for transferring the blanks individually from the magazine to the working 10 position and for centering and holding the same in axial alignment with the tools, a 15 pair of drill spindles at opposite sides of the transferring mechanism, means for automatically feeding the spindles axially toward the work, and means for varying the 20 extent of such feeding movement. It will be understood that the invention comprises other mechanism and details of construction not above enumerated. Such mechanism and the specific construction illustrated 25 in the drawings will now be described. It should be understood however that while the machine is primarily intended for center drilling both ends of a piece of work, a single drill spindle may be provided for 30 certain classes of work and the drilling may be performed otherwise than at the center of the work, or a chamfering or other tool may be used if desired, all of which is 35 within the scope of the invention.

A bed 1 supported on legs 2 has mounted thereon drill supporting heads 3 and 4. The heads are adjustable longitudinally on ways 1^a of the bed and are adapted to be 40 secured in adjusted position by the usual clamping means 5 each operated by a handle 6. Drill spindles 7 and 8 are mounted in the heads and are adapted to support drills 7^a and 8^a therein. Electric motors 9 and 10 may be provided for rotating the 45 spindles. Means are provided as herein-after described for feeding the spindles inwardly toward the work. A magazine 11 at the rear of the machine is adapted to 50 support a quantity of blanks W and a reciprocating carrier 12 is adapted to transfer the blanks individually from the magazine to a position between the drill spindles. Cooperating with the carrier is a 55 pair of work engaging members 13 by means of which the work is centered and held in a position in axial alignment with the drill spindles. The several parts of the machine just described are adapted to be synchronously 60 operated by means of a motor 14. These several parts of the machine and the operations thereof will now be more specifically described.

The magazine 11 comprises a pair of blank supporting uprights 15, each mounted on a support 16, preferably integral with

the adjacent spindle supporting head. Each upright is preferably mounted for a slight longitudinal adjustment on its support and may be secured in position by means of a clamping handle 17 engaging a clamping bolt in a T-slot 18. By this construction it will be noted that each head and magazine upright is adjustable longitudinally along the bed as a unit. In this manner the magazine may be adjusted for blanks of varying lengths and the drill spindles are always retained in approximately the desired operative position relative to the magazine and blanks fed therefrom, the means at 18 providing for a slight relative adjustment of such parts to allow for tools of slightly varying lengths and for other reasons when desired. It will furthermore be noted that each work engaging member 13 is also mounted on its adjacent spindle supporting head whereby longitudinal adjustment of each spindle supporting head also adjusts its magazine upright 15 and the opposed work engaging member 13 therewith. Means hereinafter described is provided for permitting a slight longitudinal adjustment of each work engaging member on its support.

The carrier 12 comprises a pair of work-engaging jaws including in part a pair of slides 19 each mounted in a guideway in the base of its magazine upright 15, as illustrated in Figs. 3, 7, 8, 9 and 18. A work supporting and clamping plate or jaw proper 20 is secured to the forward end of each slide by means of a bolt 21 and pin 22 engaging holes in the plate. As illustrated in Fig. 9, each plate is provided with a plurality of work engaging notches 23 therein of different sizes, and also with a plurality of holes 24 whereby the plate may be secured to the slide in any of its work engaging positions. The rear of each slide is provided with a hook-shaped element 25 adjustably secured in the slide 19 by means of a screw 26. A plunger 27 is mounted within a bore 28 of each slide and a compression spring 29 surrounding the plunger within the bore normally forces the plunger outwardly. A rod 30 mounted on a pair of levers 31 secured to a shaft 32 on a bracket 32^a bolted to the machine frame by bolts 32^b, engages the slides between the elements 25 and plunger 27 thereof. An arm 33 secured to the shaft has a roller 34 thereon engaging in a cam path 35 of a cam 36 mounted on a shaft 37. It will be seen that as the cam is rotated the carrier will be reciprocated transversely of the bed 1. A box 32^b formed on the bracket 32^a provides a receptacle for receiving extra plates 20 when not in use.

The work engaging members 13 cooperate with the carrier in centering and holding the work and each member is provided with

a V-shaped work engaging jaw 38. These members are each adjustable transversely of the bed 1 by means of a screw 39 operated by hand wheel 39^a and are each mounted on a support 40 longitudinally adjustable on a guideway 41 on its adjacent spindle supporting head. A clamp 42 is adapted to secure each support in its adjusted position opposite its co-operating work engaging plate 20. In operation a blank is adapted to be fed from the magazine to the plate 20 at the rear end of the stroke of the carrier. The blank resting on the surface 20^a of each plate is carried forward to the jaws 38 which center the blank as illustrated in Fig. 5. It will be noted that in the centering operation, the blank is held between the vertical surfaces 20^b of the plates and the jaws, the blank being raised from engagement with the supporting surfaces 20^a. The spring 29 is adapted to compress to hold the blank with a yielding pressure. The parts are held in this blank securing position during the time the roller 34 is in the concentric portion of the cam path 35, the tools being adapted to operate on the blank at such time.

As the carrier moves rearwardly, an element 43 pivoted at 43^a for movement to the left only (Fig. 5) is adapted to engage the finished blank to push the same from the plate 20 whereupon it falls into a receiving receptacle hereinafter described.

As illustrated in Figs. 1 to 4 and Figs. 10 and 11, the drill spindles are rotated from motors 9 and 10, both spindles with the motors for rotating the same being alike, a detailed description of one will suffice. As shown in Figs. 10 and 11, each spindle is rotatably mounted in a sleeve 44 longitudinally slidably mounted within the head and prevented from rotation therein by means of a key 45. The drills 7^a and 8^a are secured in the spindles by means of chucks 46 and stop members 47 are provided for limiting the depth of the drilling operation. The rear portion of each spindle is splined within a pair of integral gears 48 and 49 and supported within the bearing 50. The motor armature shaft 51 extends through a bearing 52 and has mounted thereon a pair of gears 53 and 54. An element 55 mounted between the gears 48 and 49 and provided with a handle 56 serves to shift the said gears into driving engagement with the gears 53 and 54 whereby to obtain either of two spindle rotating speeds from the motor. As seen in Figs. 10 to 12, the element 55 is adapted to slide rectilinearly in two right angular directions. Movement thereof longitudinally of the spindle is adapted to shift the gears 48 and 49. Movement thereof into either of the recesses 57 or 58 in the plate 60 is adapted to lock the gears 48 and 49 in their driving relation with gears 53 and 54 respectively. Movement thereof into the notch 59 is adapted to engage the lug 61 of the element in the aperture 62 in the gears 48 and 49 whereby to lock the spindles against rotation. The purpose of such construction is to prevent rotation of the spindle while the drill securing cap nut of the chuck 46 is being removed to change the drill. It should be noted that the relation of the notches 57, 58 and 59 is such as to provide an interlock preventing the simultaneous engagement of the spindle locking means and the drive gearing thereof.

The spindle feeding means are operated synchronously with the blank feeding and holding means, both being illustrated as operated from the shaft 37. Each spindle sleeve 44 is provided with rack teeth 63 therein engaged by a pinion 64. A pair of arms 65 is mounted on the shaft supporting pinion 64 in the head 4 and a similar pair of arms is mounted on a shaft supporting a pinion 66 in mesh with pinion 64 in the head 3. An arm 67 loosely journaled on each of said shafts extends laterally between the arms 65 (Figs. 3 and 4) and each has means thereon adapted to engage a set screw 68 and a spring pressed plunger 69 in the arms 65. Clamping screws 70 in the ends of the arms 67 are adapted to secure such arms to operating rods 71 pivoted at 71^a to one arm 72 of an operating bell-crank lever. The other arm of this lever is provided with a roller 73 slidably mounted in a guideway 74 (Fig. 6) in a bracket 75. The fulcrum of the lever is supported by rollers 76 and 76^a operating in a cam path 77 in the cam 36, and in a horizontal guideway between guide shoes 76^b on the base plate of the bracket 32^a (Fig. 6^a). It will now be seen that as the cam 36 rotates, the bell-crank lever is moved in the guideway 76^b in a general direction parallel to the shaft 37 and the rods 71 are given a longitudinal movement therefrom. With the guideway 74 adjusted to the angular position illustrated in Fig. 6, the roller 73 rides downward in the guideway 74 as the bell-crank lever is moved to the left. This rocks the bell-crank lever about its fulcrum 76, the extent of such rocking movement depending upon the angle to which the guideway 74 is adjusted. The movement of the pivot 71^a to the left (Figs. 3 and 6) is adapted to feed the drill spindles inwardly and the rocking movement of the bell-crank lever to the left therefore increases the feeding movement of the drill spindles. With the guideway 74 placed in a horizontal position, the roller 73 rides therein without any vertical movement and the bell-crank lever is therefore given no rocking movement as the cam 36 is rotated. By adjusting the bracket and guideway about the pivot 74^a to incline the guideway in the opposite direction to that illustrated

in Fig. 6, the roller 73 will be moved upwardly as the fulcrum roller 76 is moved to the left, whereby the bell-crank lever will be rocked to the right and the pivot 71^a will be moved to the right and thereby decrease rather than increase the feeding movement of the spindles relative to the movement of roller 76. In Fig. 6 the guideway 74 is set to give the maximum stroke to the spindles. A clamp 78 is adapted to clamp the bracket 75 in any of its adjusted positions. It should also be noted that as the stops 47 on the spindles engage the work and prevent further inward movement of the spindles, the spring plunger 69 yields during the continued movement of the spindle operating means.

The cam 36 is driven from motor 14 through the following mechanism (Fig. 3). A small spiral gear 79 on the motor shaft engages a large spiral gear 80 on a shaft 81. A spur gear 82 on the shaft 81 meshes with a spur gear 83 on a shaft 84 and worm 85 on the shaft 84 meshes with a worm wheel 86 on the aforesaid shaft 37. A pump 87 is adapted to be driven from the shaft 81 through a belt 88 whereby a lubricant is delivered from a tank 89 through conduits 90 to the drills. Three electric switches 91 (Fig. 1) are adapted to control the operation of the motors.

A receptacle 92 is illustrated for receiving the finished blanks as they are released from the holding means. Above this receptacle I preferably pivot an element 93. This element, in the position illustrated in Fig. 5, serves as a means to guide the finished blanks into the receptacle 92. When it is desired to remove the receptacle for emptying the same, the element 93 is raised up to the horizontal position illustrated in dot and dash lines (Fig. 5) wherein it is supported by a hook 94. In this position the element catches and supports the blanks until the receptacle is returned to place. The element may be released from the hook by raising the handle 94^a.

In some instances, it may be preferred to operate the machine through belt driven means rather than through the motors heretofore described. In Figs. 13 to 17 I have illustrated attachments adapted to be substituted directly for the said motors, such attachments being provided with belt pulleys adapted to be operated from any convenient source of power.

The attachment illustrated in Fig. 13 comprises a supporting surface or face plate 95, a supporting arm 96 providing a bearing 97 for a shaft 98. The shaft has a pulley 99 thereon operated by a belt 100. Bolts 101 extending through the face plate are adapted to secure the attachment to the machine in the same manner that motor 10 is secured by bolts 101^a. The shaft 98 is supported

in the bearing and is adapted to support gears 53 and 54 in the same manner as is done by the armature shaft of motor 10. A guard 102 is preferably provided on the attachment.

The attachment illustrated in Figs. 15 and 16 is similar to that shown in Figs. 13 and 14 except that a short shaft 103 is substituted for the motor shaft and the gears 53, 54 are driven from a gear 104 on the pulley shaft 105. The shaft 105 is supported in bearings 106 and 107 on the attachment and has a pulley 99 thereon operated by a belt 100^a. The attachment is secured by screws 101^a and a guard 102 is preferably provided. It will be noted that by this construction the spindles are adapted to be operated in opposite directions from a countershaft without the use of cross belts.

The attachment illustrated in Fig. 17 comprises the face plate 109, an extension bracket 110 supporting a bearing 111 at its outer end for a shaft 112 which shaft is adapted to be substituted for the armature shaft of the motor 14. The attachment is adapted to be secured to the machine by means of bolts 113 and the shaft is rotated from a belt pulley 114 thereon.

As heretofore stated and as shown in Fig. 2, the magazine members 15 and the work engaging members 13 are normally positioned directly opposite each other whereby the blank is held directly between such members. Furthermore the members 15 and 13 are supported on the bases of their adjacent spindle supporting heads 3 or 4 whereby, when adjusting the mechanism to the length of the blank to be operated upon, each spindle head with its magazine member and work engaging member is adjusted as a unit on the ways 1^a of the bed.

It is believed that the mechanism comprising the machine and the operation thereof will be clear without further description.

What I claim is:

1. A machine tool comprising in combination, a base, a tool spindle, a laterally movable carrier on the base having a blank supporting surface and a relatively angular blank gripping surface, the carrier being adapted to support a blank on its supporting surface and carry the same from a loading position laterally of the spindle to a tooling position adjacent the spindle, a normally fixed jaw between which and the said blank gripping surface the blank is adapted to be centered and held by the carrier for the tooling operation, the said blank supporting and gripping surfaces being adapted to perform their respective functions independently of each other, and means for feeding the spindle toward the blank and operating the carrier.

2. A machine tool comprising in combination, a base, a tool spindle, a laterally mov-

able carrier on the base having a substantially horizontal blank supporting surface and a substantially vertical blank gripping surface, the carrier being adapted to support a blank on its supporting surface and carry the same from a loading position laterally of the spindle to a tooling position adjacent the spindle, a normally fixed jaw between which and the said blank gripping surface the blank is adapted to be centered and held by the carrier for the tooling operation, and means for feeding the spindle toward the blank and operating the carrier.

3. A machine tool comprising in combination a base, a tool spindle, a laterally movable carrier on the base having a substantially horizontal blank supporting surface and a substantially vertical blank gripping surface, the carrier being adapted to support a blank on its supporting surface and carry the same from a loading position laterally of the spindle to a tooling position adjacent the spindle, a normally fixed V-shaped jaw between which and the said blank gripping surface the blank is adapted to be centered and held by the carrier for the tooling operation, the fixed jaw and carrier being so relatively positioned that in the centering and holding operation the blank is raised from the supporting surface, and means for automatically feeding the spindle toward the blank and operating the carrier.

4. A machine tool comprising in combination, a base, a tool spindle, a laterally movable carrier on the base having a blank supporting surface and a relatively angular blank gripping surface, the carrier being adapted to support a blank on its supporting surface and carry the same from a loading position laterally of the spindle to a tooling position adjacent the spindle, a normally fixed jaw between which and the said blank gripping surface the blank is adapted to be centered and held by the carrier for the tooling operation independently of the said blank supporting surface, means for adjusting the fixed jaw transversely of the spindle, and means for feeding the spindle toward the blank and resiliently operating the carrier.

5. A machine tool comprising in combination, a base, a tool spindle, a magazine for supporting a plurality of blanks, a laterally movable carrier on the base having a blank supporting surface and a relatively angular blank gripping surface, the blank supporting surface being adapted to receive a blank from the magazine and to support and carry the same therefrom to a tooling position adjacent the spindle, a normally fixed jaw between which and the said blank gripping surface the blank is adapted to be centered and held by the carrier for the tooling operation independently of the said blank supporting surface, and means for automatically

feeding the spindle toward the blank and operating the carrier.

6. A machine tool comprising in combination, a base, a tool spindle, a magazine for supporting a plurality of blanks, a laterally movable carrier slidably mounted on the base and having a substantially horizontal blank supporting surface and a substantially vertical blank gripping surface, the blank supporting surface being adapted to receive a blank from the magazine and to support and carry the same therefrom to a tooling position adjacent the spindle, a normally fixed V-shaped jaw between which and the said blank gripping surface the blank is adapted to be centered and held by the carrier for the tooling operation, the fixed jaw and carrier being so relatively positioned that in the centering and holding operation the blank is raised from the supporting surface, and means for automatically feeding the spindle toward the blank and operating the carrier.

7. A machine tool comprising in combination, a base, a tool spindle, a magazine for supporting a plurality of blanks, a horizontally movable carrier slidably mounted on the base of the magazine and having a substantially horizontal blank supporting surface and a substantially vertical blank gripping surface, the blank supporting surface being adapted to receive a blank from the magazine and to support and carry the same therefrom to a tooling position adjacent the spindle, a normally fixed jaw between which and the said blank gripping surface the blank is adapted to be centered and held by the carrier for the tooling operation, and means for automatically feeding the spindle toward the blank and operating the carrier.

8. A machine tool comprising in combination, a base, a tool spindle, a magazine for supporting a plurality of blanks, a pair of laterally movable members on the base each having a horizontal blank supporting surface and a vertical blank gripping surface, the blank supporting surfaces being adapted to receive a blank from the magazine and to support and carry the same therefrom to a tooling position adjacent the spindle, a normally fixed jaw between which and the said blank gripping surfaces the blank is adapted to be centered and held by the member for the tooling operation, means for adjusting the fixed jaw transversely of the spindle, and power operated means for synchronously feeding the spindle toward the blank and resiliently operating the member.

9. A center drilling machine comprising in combination, a base, a pair of oppositely disposed drill spindles on the base, a magazine for supporting a plurality of blanks, a pair of laterally movable members on the

- base having horizontal blank supporting surfaces and vertical blank gripping surfaces, the blank supporting surfaces being adapted to receive a blank from the magazine and to support and carry the same therefrom to a tooling position between and adjacent the spindles, a pair of fixed jaws between which and the blank gripping surfaces the blank is adapted to be centered and held by the members for the tooling operation, and means for automatically and synchronously feeding the drill spindles toward the blank and operating the members.
10. A center drilling machine comprising in combination, a base, a pair of oppositely disposed drill spindles on the base, a magazine for supporting a plurality of blanks, a horizontally movable carrier on the base having substantially horizontal blank supporting surfaces and substantially vertical blank gripping surfaces, the blank supporting surfaces being adapted to receive a blank from the magazine and to support and carry the same in a substantially horizontally direction therefrom to a tooling position between and adjacent the drill spindles, a pair of fixed jaws between which and the blank gripping surfaces the blank is adapted to be centered and held by the carrier for the tooling operation, means for adjusting the jaws transversely of the spindles, and means for automatically and synchronously feeding the drill spindles toward the blank and operating the carrier.
15. A center drilling machine comprising in combination, a base, a pair of oppositely disposed drill spindles on the base, a magazine comprising two relatively adjustable guideway members for receiving the ends of a plurality of blanks, a movable carrier adapted to receive a blank from the magazine and to support and automatically transfer the blank from the magazine to a tooling position between the drill spindles, a pair of fixed jaws against which the blank is adapted to be centered and held by the carrier for the tooling operation, means for relatively adjusting the magazine guideway members longitudinally of the spindles and for likewise relatively adjusting the jaws, and means for automatically and synchronously feeding the drill spindles toward the blank and operating the carrier.
20. A center drilling machine comprising in combination, a base, a pair of oppositely disposed drill spindles on the base, means on the base for centering a blank in the drilling position between the drill spindles and for holding the blank in such position, a pair of links operatively connected respectively to the drill spindles, a single cam for reciprocating the links to automatically and simultaneously feed the drill spindles toward the blank, means other than the cam for varying the stroke of the spindles, and power means for synchronously operating the first named means and the cam.
25. A center drilling machine comprising in combination, a base, a pair of oppositely disposed drill spindles thereon, means on the base for centering a blank in the drilling position between the drill spindles and for holding the blank in such position, a cam member provided with a cam path, a bell crank having a roller at its fulcrum seated in the cam path and one arm thereof operatively connected to the spindles to reciprocate the same, and an angularly adjustable member provided with a guideway in which the other arm of the bell crank is adapted to slide, the angular adjustment of the said member being adapted to vary the stroke of the spindles.
30. A machine tool comprising in combination, a base, a tool spindle, a movable blank carrier on the base, a rectangular plate-like blank engaging jaw mounted on the carrier and having different sized blank engaging notches in the corners thereof, means for securing the jaw to the carrier with any one of the notches in the blank engaging position, a normally fixed jaw against which the blank is adapted to be centered and held by the first named jaw, and means for synchronously and automatically feeding the spindle toward the blank and operating the carrier.
35. A center drilling machine comprising in combination, a base, a pair of oppositely disposed drill spindles on the base, a movable blank carrier on the base comprising two spaced elements, a rectangular plate-like blank engaging jaw mounted on each element, the jaws each being provided with different sized notches in the corners thereof, means for securing the jaws to the elements with any of the notches in the blank engaging position, a pair of fixed jaws against which the blank is adapted to be centered and held by the first named jaws, means for adjusting the fixed jaws transversely of the spindles, and means for automatically and synchronously feeding the drill spindles toward the blank and operating the carrier.
40. A center drilling machine comprising in combination, a base, a pair of oppositely disposed drill spindles on the base, a movable blank carrier on the base comprising two substantially horizontally movable slides, a rectangular plate-like blank engaging jaw mounted on each slide, the jaws each being provided with different sized notches in the corners thereof, means including bolts for securing the jaws to the slides, the jaws each being provided with a plurality of spaced bolt-receiving holes therein whereby the jaws may be mounted with any of the said notches in the blank engaging position, a pair of fixed jaws against which the blank

is adapted to be centered and held by the first named jaws, means for adjusting the fixed jaws transversely of the spindles, and means for automatically and synchronously feeding the drill spindles toward the blank and operating the carrier.

17. A machine tool comprising in combination, a base, a support mounted on one end thereof, a spindle in the support, means whereby the support may be adjusted on the base longitudinally of the spindle and secured in adjusted position, a magazine comprising two guideway members adapted to receive the ends of a plurality of blanks, one of said members being mounted on the support and adjustable therewith toward and from the other member, and means for transferring a blank from the magazine to the spindle and for holding the same in position for a tooling operation.

18. A machine tool comprising in combination, a base, a support mounted on one end thereof, a spindle in the support, means whereby the support may be adjusted on the base longitudinally of the spindle and secured in adjusted position, a magazine comprising two guideway members adapted to receive the ends of a plurality of blanks, one of said members being mounted on the support and adjustable therewith toward and from the other member, a fixed jaw on the support laterally of the spindle, and means for transferring a blank from the magazine to the jaw and centering and holding the same therein in position for a tooling operation.

19. A machine tool comprising in combination, a base, a support mounted on one end thereof, a spindle in the support, means whereby the support may be adjusted on the base longitudinally of the spindle and secured in adjusted position, a magazine comprising two guideway members adapted to receive the ends of a plurality of blanks, one of said members being mounted on the support and adjustable therewith toward and from the other member, a fixed jaw on the support laterally of the spindle, a movable carrier supported by the support opposite the fixed jaw, and means for operating the carrier to transfer a blank from the magazine to the jaw and to center and hold the same therein in position for a tooling operation.

20. A machine tool comprising in combination, a base, a support mounted on one end thereof, a spindle in the support, means whereby the support may be adjusted on the base longitudinally of the spindle and secured in adjusted position, a magazine comprising two guideway members adapted to receive the ends of a plurality of blanks, one of said members being mounted on the support and adjustable therewith toward and from the other member, a fixed jaw on

the support laterally of the spindle, a movable carrier on the said one member opposite the fixed jaw on the support, means providing an adjustment on the support of the said one member longitudinally of the spindle, and means for operating the carrier to transfer a blank from the magazine to the jaw and to center and hold the same therein in position for a tooling operation.

21. A machine tool comprising in combination, a base, a support mounted on one end thereof, a spindle in the support, means whereby the support may be adjusted on the base longitudinally of the spindle and secured in adjusted position, a magazine comprising two guideway members adapted to receive the ends of a plurality of blanks, one of said members being mounted on the support and adjustable therewith toward and from the other member, a fixed jaw on the support laterally of the spindle, a movable carrier slidably mounted on the base of the said one member opposite the fixed jaw on the support, and means for sliding the carrier to transfer a blank from the magazine to the jaw and to center and hold the same therein in position for a tooling operation.

22. A center drilling machine comprising in combination, a base, a pair of supports mounted respectively on opposite ends of the base, a pair of oppositely disposed drill spindles rotatably mounted respectively on the supports, a magazine comprising two guideway members respectively mounted on the supports and adapted to receive the ends of a plurality of blanks, means for transferring a blank from the magazine to the spindles and for centering and holding the same in the drilling position therein, means for moving the drill spindles toward the blank, and means providing a relative adjustment of the supports longitudinally of the spindles.

23. A center drilling machine comprising in combination, a base, a pair of supports mounted respectively on opposite ends of the base, a pair of oppositely disposed drill spindles rotatably mounted respectively on the supports, a magazine comprising two guideway members respectively mounted on the supports and adapted to receive the ends of a plurality of blanks, a fixed jaw mounted on each support laterally of its spindle, means for transferring a blank from the magazine to the jaws and for centering and holding the same in the drilling position therein, means for moving the drill spindles toward the blank, and means providing a relative adjustment of the supports longitudinally of the spindles.

24. A center drilling machine comprising in combination, a base, a pair of supports mounted respectively on opposite ends of the base, a pair of oppositely disposed drill

spindles rotatably mounted respectively on the supports, a magazine comprising two guideway members respectively mounted on the supports and adapted to receive the ends 5 of a plurality of blanks, a fixed jaw mounted on each support laterally of its spindle, a movable carrier on the supports opposite the fixed jaws, means for operating the carrier to transfer a blank from the magazine to the jaws and to center and hold the same in the drilling position therein, means for moving the drill spindles toward the blank, and means providing a relative adjustment 10 of the supports longitudinally of the 15 spindles.

25. A center drilling machine comprising in combination, a base, a pair of supports mounted respectively on opposite ends of the base, a pair of oppositely disposed drill 20 spindles rotatably mounted respectively on the supports, a magazine comprising two guideway members respectively mounted on the supports and adapted to receive the ends 25 of a plurality of blanks, a fixed jaw mounted on each support laterally of its spindle, a carrier slide slidably mounted on each support opposite the fixed jaws, means for operating the slides to transfer a blank from the magazine to the jaws and for 30 centering and holding the same in the drilling position therein, means for moving the drill spindles toward the blank, and means whereby the supports may be adjusted 35 toward and from each other.

35. 26. In a machine tool, the combination of a rotary spindle, gearing for rotating the spindle, means for shifting the gearing to vary the speed of spindle rotation, means for locking the spindle against rotation, and a 40 single handle for operating both means.

27. In a machine tool, the combination of a rotary spindle, gearing for rotating the spindle, means for shifting the gearing to vary the speed of spindle rotation, means for 45 locking the spindle against rotation, and means permitting the engagement of the spindle locking means only when the gearing is out of driving engagement.

28. In a machine tool, the combination of 50 a rotary spindle, gearing for rotating the spindle, means for shifting the gearing to vary the speed of spindle rotation, means for locking the spindle against rotation, a single handle for operating both means, and means 55 permitting the engagement of the spindle locking means only when the gearing is out of driving engagement.

29. In a machine tool, the combination of 60 a rotary spindle, gearing for rotating the spindle comprising a pair of connected gears splined to the spindle, means for shifting the said pair of gears to vary the speed of spindle rotation, means adapted to engage the said pair of gears to prevent rotation 65 thereof, a single handle for operating both

means, and a plate, through which the handle passes, slotted to permit the operative engagement of the spindle locking means only when the gearing is out of driving engagement.

30. In a machine tool the combination of a rotary spindle, gearing for rotating the spindle comprising a pair of connected gears splined to the spindle, means for shifting the said pair of gears to vary the speed of 70 spindle rotation, means adapted to engage the said pair of gears to prevent rotation thereof, and a single handle for operating both means.

31. In a machine tool the combination of a rotary spindle, gearing for rotating the spindle comprising a pair of connected gears splined to the spindle, means for shifting the said pair of gears to vary the speed of 80 spindle rotation, a tooth on the shifting means adapted to engage in a socket in the said pair of gears to prevent rotation thereof, and a handle for the shifting means.

32. In a machine tool the combination of a rotary spindle, gearing for rotating the spindle comprising a pair of connected gears splined to the spindle, a shifting member 90 adapted to slide in one direction to shift the said pair of gears to vary the speed of spindle rotation, a tooth on the shifting member 95 adapted to be engaged in a socket in the said pair of gears by a sliding movement of the shifter member at right angles to its gear shifting movement to prevent rotation of the gearing and spindle, and a handle for operating the shifter member.

33. In a metal working machine comprising a base and means for holding a blank and a tool for operating on the blank, the combination of means mounted on the machine and adapted in one position to guide the finished blanks into a receiving receptacle and in another position to receive and support the blanks as they fall from the said holding means, and means for holding 100 the guiding and supporting means in either of its said positions.

34. In a metal working machine comprising a base and means for holding a blank and a tool for operating on the blank, the combination of means pivoted on the machine and adapted in one position to guide the finished blanks into a receiving receptacle, and other means for supporting the first means in a position to receive and support the blanks as they fall from the said holding means.

35. In a metal working machine comprising a base and means for holding a blank and a tool for operating on the blank, the combination of a plate pivoted at one edge on the machine and adapted in one position to guide the finished blanks into a receiving receptacle, and an element adapted to engage the opposite edge of the plate to support 125

port the same in a position to receive and support the blanks as they fall from the said holding means.

36. In a machine tool, the combination of a support, means for holding a piece of work and for operating thereon, gearing for operating the said means, two optionally usable power mechanisms each adapted to be detachably secured to the support in operative connection with the gearing for driving the same, one of the said mechanisms being an electric motor and the other mechanism being a belt driven attachment comprising a bracket having a driving pulley supported

therein, both said mechanisms and the support being provided with cooperating supporting means including bolt holes adapted to be placed in alignment for mounting either mechanism on the support, and bolts for engaging in the said holes to secure either mechanism to the support with either the motor armature shaft or the said pulley in operative connection with the said gearing.

In testimony whereof, I hereto affix my signature.

JOHN J. THACHER.
